DEEP WELL PUMP

William F. Tebbetts, Jr., Los Angeles, Calif.

Application March 11, 1940, Serial No. 323,325

8 Claims. (Cl. 103—46)

The present invention relates generally to deep well pumps and although necessarily embodying a pumping device in practise, relates more particularly to a subsurface actuator controlled by pressure at the surface, with the primary object of simplifying and reducing the cost of production of known devices of this nature, as well as increasing flexibility of application and use.

A further object involves the adaptability of the invention to various types of oil well pumping devices.

A still further object is the provision of a pump actuator having but a single moving part without valves and of durable, long-wearing nature by reason of its simple, rugged character, and the elimination of wear from sand.

A still further object relates to the readiness and ease with which the actuator and pumping device may be removed as a unit from a well, and its adaptability to ready regulation as to speed by the regulation of pressure input.

Another object of the invention relates to the adaptability of the actuator to the use of either a compressible or a non-compressible pressure fluid.

Many other objects will be understood in connection with the hereinafter specified advantages in the construction and use of the invention which, in its preferred form, will be described in detail and more thoroughly appreciated from such description, by reference to the accompanying drawings, illustrating the same and forming a part of this specification.

In these drawings,

Figure 1 is a sectional side view of my invention, with many parts thereof broken away for better illustration, and with the lower pump portion thereof in detached elevation.

Figure 2 is a vertical sectional view through the lower pump portion of the apparatus, somewhat enlarged, showing a usable type of oil well pump.

Figure 3 is a vertical sectional view through a portion of the apparatus, showing certain of the parts thereof, including the motor piston working barrel dropped to a position for removal of the standing valve.

Figures 4 and 5 are detail transverse sectional views taken respectively on lines 4—4 and 5—5 of Figure 3, and,

Figure 6 is a detail perspective view of the upper portion of the lower motor piston extension.

Referring now to the above described drawings, and particularly to Figure 1, my invention comprises a pump actuator which essentially com-

prises a motor piston 10 of hollow cylindrical form, slideable vertically in an elongated motor working barrel 11 to the upper end of which an upper cushion cylinder 12 is connected. This cylinder has an axial bore 13 of substantially reduced diameter with respect to the working barrel, to receive therein the slidably interfitting, reduced tubular upstanding piston extension 14 when the piston 10 moves toward the upper limit of its stroke.

To the lower end of the working barrel 11 of the motor piston 10 is connected a lower cushion cylinder 15 having a lower axial bore 16 to receive in slidably interfitting relation the reduced tubular depending piston extension 17 when the piston moves downwardly to its lower position in the barrel 11. The barrel 11 and its upper and lower cushion cylinders 12 and 15 thus constitute a rigid motor piston working unit with the motor piston movable vertically in the central portion or barrel 11, and having upper and lower reduced extensions 14 and 17.

In operation, the extension 14 enters the cylinder bore 13 when the piston moves upwardly, and cuts off direct communication between the space 18 above the piston and the bore 13, this extension 14 having a vertical series of openings 19 in its wall affording limited communication between said space 18 and the said cylinder bore 13, to thus cushion the piston as it nears the limit of its upward stroke.

Similarly the lower piston extension 17 enters cylinder bore 16 when the piston moves downwardly and closes the space 20 below the piston except to the exterior of the barrel 11 through a vertical series of openings 21 with which the lower portion of the wall of the barrel is provided. The space 20 below the piston is then afforded gradually limited communication with the exterior of the barrel or the space within a casing 22 surrounding the same and spaced therefrom, until the piston reaches the end of its downward travel adjacent the upper end of the lower cylinder 15.

To the lower end of the lower extension 17 of the piston 10, a somewhat smaller connecting tube 17a depends substantially below the working unit of the actuator and, as presently described, is connected at its lower end to the plunger of a pump, so that as the motor piston moves upwardly, oil is taken into the barrel of the pump and as the motor piston moves downwardly such oil is forced up the connecting rod or tube 17a and through the motor piston into the upper space 18 of the barrel 11.

The casing 22 above referred to is connected at

its upper end to a casing head 23 by which it is supported, and is in open communication at its said upper end with a laterally projecting pressure receiving and outlet pipe 24 connected to said head.

The motor piston unit is supported in vertically adjustable relation in the casing 22 by a suspension tube 25 whose lower end is connected to the upper cylinder 12 and whose upper portion extends above and through the casing 23 in which it is held in adjusted position by slips 26. It will be noted that the casing head 23 supports packing 27 therein around the suspension tube 25 at a point above the pipe 24 and that above the casing head the extended portion of the pipe or tube 25 has a manual cut off valve 28 and is connected to a pressure receiving and production oil pipe 29 by readily detachable means.

The pipes 24 and 29 are shown extending into one side of the casing 30 of a piston type of control valve, the valve member 31 of which, when moved to one position, places pipe 29 in communication with a pressure supply pipe 32 and pipe 24 in communication with a pressure relief pipe 33. In its other position valve member 31 places pipe 29 in communication with a production oil outlet pipe 34 and places pipe 24 in communication with the pressure supply pipe 32, and at the same time closes pressure relief pipe 33.

At one end, valve member 31 may be provided exteriorly of the valve casing 30 with the core 35 of a solenoid having two coils 36 and 37, each of which is connected at one side to one side of a battery or other suitable source of current supply 38, these connecting wires being indicated at 39 and 40 respectively.

At its other side coil 36 is connected by a wire 41, to the movable piston part 42 of a pressure actuated, spring controlled switch, which part is exposed in a switch box 43 to pressure in pipe 29, and is normally spaced by its spring, from the stationary contact piece 44. The contact piece 44 is connected by a wire 45 with the other side of the battery 38.

Similarly, the other side of solenoid coil 37 may be connected by a wire 46 to the movable piston part 47 of a pressure actuated, spring controlled switch, exposed in a switch box 48 to pressure in pipe 24. The switch part 47 is normally spaced by its spring from a stationary contact 49, connected by a wire 50 to the battery 38.

Thus when pressure in pipe 24 reaches a point where the spring of switch part 47 is overcome, this switch part moves into contact with part 49 and a circuit is closed through the solenoid coil 37, thus shifting the piston valve 31 to the position shown in Figure 1. Thus production pipe 34 is closed, pressure supply pipe 29 is opened to supply pipe 32, and pressure relief pipe 33 is opened to pipe 24. The result is a vent or outlet is opened for pressure within the casing 22 around the motor unit and thus for the pressure space 20 within the piston barrel 11 below piston 10.

At the same time pressure is supplied through pipe 29 into the upper end of suspension pipe 25 and through the latter into the space 18 of the barrel above the piston so that it effectively operates against the full diameter of the piston 10 and thus creates a differential between the same and any oil pressure rising through the piston by reason of its downward movement and the downward movement thereby of the plunger

of the oil well pump which is of substantially smaller bore than that of the piston.

Suitable pressure, either clean oil or gas may be supplied through supply pipe 32 from any suitable source for operating the piston, and it may in some instances be of advantage to utilize a compressible fluid, such as gas, for the downward stroke of the piston 10 in the manner above described.

As the piston 10 moves downwardly in its barrel 11 for the reasons above set forth, it gradually closes off the openings 21 of the wall of the barrel and thus creates an increasing hydraulic cushion which adds to the pressure of that supplied as above and that of the oil upflowing through the piston 10 into the space 18 and suspension pipe 25. This pressure finally reaches a point where it overcomes the spring of piston switch 42 whereupon the latter is shifted against contact 44, thus closing a circuit through solenoid coil 36 and shifting the piston valve 31 to its other position from that shown in Figure 1.

In its above mentioned position, valve 31 places pipe 29 in communication with production outlet pipe 34, and pressure supply pipe 32 in communication with pipe 24, and at the same time closes pressure outlet pipe 33. This position of the parts provides for the flow of clean oil through pipe 24 into the casing and from the latter into the lower space 20 of the motor barrel through openings 21, thus gradually raising the motor piston 10 and forcing the previously raised oil from the upper space 18 upwardly through pipes 25 and 29 to the production outlet pipe 34.

The use of clean oil is important in this latter operation, since it functions to clean the barrel 11 in advance of the upwardly moving motor piston 10. For this purpose piston 10 has a vertical groove in its external surface at its lower end as seen at 51 in Figures 1 and 3, below its rings 52, and an annular external groove 53 above said rings. It is also provided interiorly thereof with a tubular conduit 54, one end of which is in communication with groove 51 and the other end of which is in communication with groove 53. In this conduit is a check valve 55 which opens upwardly toward annular groove 53.

During upward movement of the motor piston 10, pressure in the lower space 20 forces sufficient clean oil through conduit 54 and, by way of groove 53, around the upper portion of the piston, to thoroughly scavenge the wall of the barrel 11 and wash upwardly any sand which may have settled from the oil in the upper space 18.

It should be remembered that during the above cleaning operation, while the lower space 20 of the barrel has nothing but clean oil therein, the upper space 18, being in the production line, may have sandy oil therein, which in the absence of means for lubricating and cleaning the path of the piston, would mean rapid wear of the relatively moving parts.

Obviously the actuator as thus described will function with many small bore types of pumps, in fact any standard oil well pump of sufficiently small bore to allow a differential area between such bore and the bore of the motor working barrel, may be used. One such pump has, for purposes of illustration only, been shown in Figures 1 and 2. The lower end of casing 22 may, for example, be connected by a reducing collar 56 to the upper end of a pump jacket or barrel 57 in which a plunger 58 reciprocates with its travelling valve 59. This plunger is connected in any suitable manner at its upper end to the lower end

of the connecting tube 17a and may thus be readily respaced in its barrel or jacket 57 by raising or lowering the suspension pipe 25 with respect to the casing head 23.

In the fluid pump illustrated, the lower end of the barrel or jacket 57 is shown as connected by a top collar 60 to a nipple 61, whose lower end may be connected by a lower or tubing collar 61a to an extension shoe 62 having therein means providing for the ring or other lock 63 of the standing valve cage 64.

To the cage 64, above the standing valve 65, is secured the standing valve puller pin 66, having outstanding trunnions for cooperation with the internal bayonet grooves 67 of the standing valve puller bushing 68 carried by the lower end of the pump plunger 58 below the travelling valve 59.

The pulling of the standing valve, in this instance, requires that the pump plunger 58 be turned from the surface of the ground, and it will be noted that the suspension pipe 25, though capable of ready lowering to permit the downward movement of the bushing 68 to the puller pin 66, cannot convey turning movement to the motor piston and connecting tube 17a. For this reason the depending motor piston extension 17 has an external vertical rib 69 as plainly seen in Figures 1, 5 and 6.

When the motor piston 10 moves downwardly, its extension 17 moves into slidably interfitting relation within the bore 16 of cylinder 15, as hereinbefore stated, the upper portion of said cylinder having a counter-bore 70 into which the rib 69 of said extension 17 drops. Cylinder 15 has in its said counter-bore a vertical rib 71, as plainly seen in Figure 5, and thus with the motor piston in lowered position, and the rib 69 in counter-bore 70 and circumferentially opposed to rib 71, turning movement may be communicated from the motor working barrel 11, and consequently from the suspension pipe 25 to the motor piston 10 and its depending extension 17 and connecting tube 17a, for the above purpose.

Preferably, the ribs 69 and 71 have tapered lower and upper ends respectively, so that in normal operation of the motor piston, there will be no danger of the interruption of its full downward movement by reason of endwise engagement of these ribs.

It will be readily understood from the foregoing that in case the pump actuator of this invention is used with a pump such as that illustrated, and it becomes desirable to pull the standing valve, it is only necessary to first see that the motor piston is at the lowermost point of its downstroke, and then close the manual valve 28 in that portion of the suspension pipe 25 above the casing head 23. This will hold the pressure in the pipe and consequently hold the piston in lowered position.

The pipe 25 is then slightly raised, after detachment from pipe 29, the slips 26 are removed, and pipe 25 lowered until bushing 68 is around the puller pin 66. At this time the rib 69 will be within the counter-bore 70, and thus pipe 25 may be turned and such turning movement communicated through connecting tube 17a, to turn the pump plunger 58 and engage puller pin 66 in the bayonet groove 67. Then, upon removing the casing head clamp and the packing 27 and elevating the suspension pipe 25, the entire working device, including the standing valve, may be easily withdrawn by reason of dropping the fluid load.

The invention thus provides a very flexible pump actuator, which is without sub-surface valves, which is readily adjustable for the pur-

pose of respacing the pump plunger connected thereto, is simple in construction, economical in manufacture and in use, and one in which the speed of operation may be easily regulated by the pressure input.

One of the important advantages of the invention, partially involved in the pressure washing of the motor piston wall by clean oil from the lower chamber or space 20 of the barrel 11, lies in the fact that since the outflow line for production fluid is confined to the connecting tube 17a, above the standing valve, clean fluid from space 20 may also proceed downwardly under pressure and lubricate the pump plunger as well as wash and cleanse the wall against which it works, so that all working parts of the pump as well as the pump actuator will be substantially protected from, and proof against, sand wear.

Moreover, while I have shown and described the best mode so far devised for carrying the invention into practise, it may be susceptible of changes both as to construction and use, and should be understood as including all such changes and modifications thereof as fall within its spirit and within the terms of the appended claims.

Having thus fully described my invention, what I claim is:

1. In a deep well pumping mechanism, a casing, a casing head thereon, a suspension pipe depending into the casing from said head, means for alternating the feed of pressure fluid into said casing and said suspension pipe, a barrel within, and spaced from, the casing, and in communication at its lower portion therewith, said barrel being in connection and open communication at its upper end with said suspension pipe and supported thereby, a well pump of substantially smaller bore than said barrel supported by the lower end of the casing and having a vertically reciprocating plunger, a hollow valveless motor piston reciprocating in said barrel and subject to pressure at its lower end from the casing and at its upper end from the suspension pipe, and a connecting tube depending from said piston and in connection at its lower end with the pump plunger and forming a production outflow line in constant open communication through the piston, with upper portion of the barrel and the suspension pipe.

2. In a deep well pumping mechanism, a sub-surface pump actuator including a vertically reciprocating valveless motor piston having a passage vertically therethrough, a barrel in which said piston operates, a pressure feed pipe having communication with the barrel below the piston, a combined pressure feed and production outflow pipe in communication with the barrel above the piston, and supporting the barrel in rotatable and vertically adjustable relation, a connecting tube depending from the piston through the barrel, pressure controlled means for alternating the feed of pressure through said pressure feed pipes, a well pump of smaller bore than the barrel and including an operating plunger connected to and communicating with the lower end of said connecting tube, and means forming a rotatable connection between the piston and the barrel when the piston is in the lower portion of the barrel.

3. The combination with a small bore well pump, a pump actuator therefor, including a reciprocating motor piston, a barrel in which said piston reciprocates, means for alternating the feed of pressure fluid to the upper and lower

ends of said barrel, means depending from the piston and in communication with the barrel above the piston for connecting the same to said well pump, said piston having external grooves adjacent its upper and lower ends, and a valved conduit therein communicating between said grooves and having a pressure receiving end open through the lower groove into the space below the piston.

4. In a deep well pumping mechanism, in combination with a small bore pump including a jacket and a plunger, a sub-surface actuator including a hollow valveless motor piston, a barrel of substantially greater bore than said pump in which said piston reciprocates, a tubular connecting rod depending from said piston and connected to said pump plunger to form with the piston a production outflow line from the plunger into the barrel above the piston, a casing around and spaced from said barrel and connected at its lower end to the pump jacket, a casing head at the upper end of said casing, a pressure feed pipe opening into said casing, said barrel having a vertical series of openings adjacent to its lower end communicating between its space below the piston and the space within the casing, a suspension pipe in connection and communication at its lower end with the upper end of the barrel and extending at its upper portion through and above the casing head, means for adjustably supporting the suspension tube in the casing head, a pressure feed and production outflow pipe connected to the external portion of said suspension pipe above the casing head, pressure controlled means for alternating feed of pressure into the said pressure feed pipes, and a reduced upstanding neck portion carried by the piston and movable upwardly therewith into the suspension pipe and provided with a vertical series of openings through the wall thereof.

5. In a deep well pump, a small bore well pump including a reciprocating plunger, a fluid pressure actuated motor piston having a constantly open passage therethrough and presenting a top surface of substantially greater area than the pump bore, a barrel in which said piston is slideable and into which the upper end of the piston passage opens at all times, a tube rising from the pump plunger and connected in constantly open communication at its upper end with the passage of the piston to thus provide for the rise of well liquid from the well pump into the upper portion of the barrel during downstroke of the piston and plunger, said barrel having fluid pressure receiving means in its lower portion for causing upward movement of the piston, and a combined fluid pressure and production pipe rising from the upper end portion of the barrel and through which fluid pressure acts against the said upper surface of the piston to cause its downstroke in the presence of, and against, the rising liquid.

6. In a deep well pumping mechanism, a casing, a combined fluid pressure receiving and liquid production pipe depending within the casing, means for providing fluid pressure within the casing and within the said production pipe, a barrel within the casing connected, and in constantly open communication, at its upper end portion with said production pipe and in com-

munication at its lower portion with the casing, a well pump of substantially smaller bore than said barrel, located in the casing below the barrel and including a reciprocating plunger, a connecting tube rising from said plunger into the barrel, a hollow valveless motor piston slidably interfitting the barrel and fixed on the upper end of said tube to form with the latter an outflow line in constant open communication with the upper portion of the barrel and production pipe during both upward and downward strokes of the piston, said piston presenting a pressure surface around its top opening of greater area than the bore of the pump whereby to force upflow of liquid through the motor piston from the plunger tube into the production pipe against fluid pressure in said pipe acting to force the piston in a downward direction.

7. In combination with a small bore well pump having a plunger, a tube rising from said plunger for the upward flow of liquid on the downstroke of the plunger, a cylindrical barrel into which the upper end of said tube extends, a motor piston fixed on the upper end of the tube and slidably interfitting the barrel, having a constantly open liquid passage through which the plunger tube is in communication at all times with that portion of the barrel above the piston, a liquid outflow pipe in constant open communication with the upper portion of the barrel and, through the piston, with the plunger tube, said motor piston presenting an upper fluid pressure receiving surface of greater area than the bore of the pump for causing downward movement of the piston and the pump plunger by outflow pipe pressure and in the presence of, and against, upflow of liquid from the plunger through the piston into the outflow pipe, and means for alternately feeding pressure into the lower portion of the barrel below the motor piston, and downwardly through the outflow pipe against the said upper surface of the motor piston.

8. In a deep well pump, in combination, a valveless motor piston having a fluid passage therethrough, a barrel in which said piston is vertically slideable and into the upper portion of which the fluid passage of the piston is open at all times, a well pump having a plunger, a tube connecting the piston with said pump plunger and by means of which well liquid is forced upwardly through the piston passage when the piston and plunger are on the downstroke, an eduction pipe in constant open communication with the upper portion of the barrel to receive well liquid therefrom, and means for alternately providing clean pressure fluid, and relieving pressure thereof, within the lower portion of the barrel below the piston, whereby the latter, the upper surface of which is exposed at all times to the pressure of the liquid rising in the eduction pipe, will be alternately moved upwardly and downwardly and at the same time thoroughly lubricated and flushed by clean fluid, said upper surface of the piston presenting an area substantially greater than the bore of the pump, whereby upon relief of fluid pressure below the piston, fluid pressure above the latter will cause downward movement thereof against the pressure of well liquid rising therethrough.

WILLIAM F. TEBBETTS, JR.
